UNITED STATES PATENT OFFICE.

EDWARD L. EAGAN, OF DANVILLE, ILLINOIS.

RAILWAY-TRACK JACK.

Application filed October 22, 1923. Serial No. 670,139.

To all whom it may concern:

Be it known that I, EDWARD L. EAGAN, a citizen of the United States, residing at Danville, in the county of Vermilion and State 5 of Illinois, have invented certain new and useful Improvements in Railway-Track Jacks; and I do declare the following to be a full, clear, and exact description of the invention, such as will enable others skilled in 10 the art to which it appertains to make and use the same.

It is required by railway regulations, that jacks used to lift track rails for repair work, shall be placed at the outer side of the rail 15 being lifted, so that if the jack should be struck by a train, it will merely be knocked aside and there will be no danger of derailing the train. When the jack is placed in the required manner, for instance, when working 20 on a fill, the track-hand operating the jack, must often stand on insecure footing at the side of the track and he cannot therefore operate the jack at all easily.

It is the principal aim of my invention 25 to provide an improved form of jack which will comply with regulations but is provided with an operating lever which may be extended inwardly from the rail being lifted, permitting the operator to stand on the 30 solid footing between the rails whenever advisable, instead of standing at the outer side of the track. Provision is made however to allow the operating lever to extend in the usual outward direction, when it is dangerous 35 for the operator to stand between the rails, for instance, on a foggy day when approaching trains cannot be seen until dangerously near.

Another aim is to provide a jack which 40 may be operated with an ordinary track wrench instead of requiring a special lever, thereby decreasing the amount of equipment which the track-hands must carry from place to place along the track.

With the foregoing in view, the invention 45 resides in the novel subject matter herein-after described and claimed, the description being supplemented by the accompanying drawings.

Figure 1 is a rear elevation partly broken 50 away and in section showing the improved jack.

Figure 2 is a side elevation.

Figure 3 illustrates a transverse sectional view through a railway track showing the 55 manner of using the jack with its operating lever extending toward the center of the track.

Figure 4 is a complete rear edge elevation.

Figure 5 is a central vertical longitudinal 60 sectional view with parts in elevation.

Figure 6 is a detail vertical section illustrating the manner in which the pawls may be released from the toothed shank of the 65 jack.

Figures 7 and 8 are perspective views of the two pawls.

Figure 9 is a perspective view of the oscillating carrying member for the pawls.

Figure 10 is a detail sectional view as indicated by line 10—10 of Fig. 6.

Figure 11 is a perspective view of the oscillating operating member for the pawl mechanism, which is in the present instance operated by an ordinary track wrench.

In the drawings above briefly described, which illustrate the preferred form of construction, the numeral 1 designates a standard having the usual hollow foot 2 for insertion under a rail to be lifted, said standard being provided with a straight uninterrupted edge 3 for contact with the outer side of the rail, as shown in Fig. 3. At its upper end, the standard 1 is provided with two projecting frame-like portions 4 which extend 80 from the edge of said standard remote from the edge 3, the two projections 4 being preferably connected by a suitable handle 5.

An ordinary toothed jack shank 6 is slidably mounted in the standard 1 and is provided at its lower end with the usual rail-lifting foot 7 which extends from the edge 3. A pair of gravity-applied pawls 8 and 9 co-operate with the teeth of the shank 6 and are pivotally supported by a carrying lever 10 which is pivoted at 11 between the lower ends of the projections 4, the pivot or fulcrum 11 being between the pivots of the pawls 8 and 9, so that as one pawl moves downwardly, the other moves upwardly. An 100 angular arm 12 is shown extending outwardly from the lower pawl 9, with its outer end in spaced relation with a rigid post 13 extending from one side of the jack stand-

ard 1, so that by placing a track wrench or other suitable device between the arm and post, the pawl 9 may be released and this pawl may be forced against the pawl 10 to 5 in turn release the latter. If desired, the upper end of the pawl 8 may be provided with a releasing link 14 of any suitable form. The pawls are preferably mounted upon the carrying lever 10, in the manner illustrated 10 in Figs. 5 to 10 inclusive, but other mountings could be used if desired.

An oscillatory operating member 15 is suitably mounted at 15^a between the upper ends of the projecting standard portions 4 15 and this operating member is connected with the pawl mechanism, in any suitable manner, for instance by a link 16 pivoted at one end to said operating member and pivoted at its other end to the lever 10. It may here 20 also be stated that pawl mechanisms other than that shown, may be used and operated by the member 15. The link 16 preferably depends from the inner end of the operating member 10 and the outer or upper end of 25 the latter is provided with a lateral extension 17 which projects in a direction parallel with the pivot 15^a. In the construction shown, the extension 17 is formed with opposite flat sides 18 which permit said extension to be received between the jaws of an 30 ordinary track wrench 19, the handle of this wrench being preferably extended by a piece of pipe or the like, as indicated at 20. Obviously, the wrench 19 or other hand-lever 35 which may be associated with the operating member 15 may extend over the track, even though the jack is properly positioned at the outer side of one of the track rails as indicated in Fig. 3, thus permitting the operator 40 to stand on solid footing, which allows him to operate the jack much more easily. Whenever it is inadvisable to stand between the rails however, the wrench 19 or its equivalent, may be extended outwardly from the 45 jack and the operator may stand at the side of the track, in the usual way.

Particular attention is directed to the facts that the standard 1 is provided with the usual straight uninterrupted edge 3 for 50 disposition against the outer side of the rail being lifted; the entire pawl mechanism is located at the opposite edge of the standard to interfere in no manner with raising the rail to any desired extent, and the lever 19 55 may be extended from the operating member 15 of the pawl mechanism, beyond the first named edge of the jack standard, or in the opposite direction if desired.

The construction of the device is rather 60 simple and comparatively inexpensive, yet it will be seen that such construction is a marked improvement over the common track jacks now in operation. As excellent results 65 are obtainable from the details disclosed, they may be followed, but within the scope

of the invention as claimed, changes may be made, it being obvious that the invention may be embodied in numerous forms.

I claim:

1. A railway track jack comprising a 70 standard having a straight uninterrupted edge to abut the outer side of a rail, a shank slidably associated with said standard and having the usual rail-lifting foot extending beyond said edge, shank-lifting pawl mechanism at the edge of the standard opposite said foot, and an operating lever for said pawl mechanism extending from the latter beyond the first named edge of said standard to permit the operator to stand between the rails. 75

2. A railway track jack comprising a standard having a straight uninterrupted edge to abut the outer side of a rail, a shank 80 slidably associated with said standard and having the usual rail-lifting foot extending beyond said edge, shank-lifting pawl mechanism at the edge of the standard opposite said foot, and a hand-lever extensible beyond either of said edges of the standard 85 for operating said pawl mechanism.

3. A railway track jack comprising a standard having a straight uninterrupted edge to abut the outer side of a rail, a shank 90 slidably associated with said standard and having the usual rail-lifting foot extending beyond said edge, shank-lifting pawl mechanism at the edge of the standard opposite said foot, said pawl mechanism having an oscillatory operating member provided with 95 a portion extending laterally beyond one side of the standard, and an operating lever engageable with said projection and extensible beyond either of the aforesaid edges of the standard. 100

4. A railway track jack comprising a standard having a straight uninterrupted edge to abut the outer side of a rail, a shank 110 slidably associated with said standard and having the usual rail-lifting foot extending beyond said edge, shank-lifting pawl mechanism at the edge of the standard opposite said foot, said pawl mechanism having an oscillatory operating member provided with 115 a portion extending laterally beyond one side of the standard, to be engaged by an operating lever.

5. A structure as specified in claim 4; said laterally extending portion of said operating member having opposite parallel sides to 120 permit reception in a track wrench.

6. A railway track jack comprising a standard having an uninterrupted edge for contact with the outer side of a rail, the opposite edge of said standard having a 125 projecting portion at its upper end, a shank slidable in said standard and having the usual rail lifting foot extending from the first named edge thereof, shank-lifting pawl mechanism mounted in said projecting por- 130

tion of the standard, and a pivoted operating member for said pawl mechanism mounted in said projecting portion of the standard, said operating member extending above said projecting portion of said standard and having a flat-sided projection above said projecting portion and extending in a direction parallel with the pivot of said

operating member for engagement by a track wrench to operate the jack while the operator stands either at the outer or the inner side of either track rail.

In testimony whereof I have hereunto affixed my signature.

EDWARD L. EAGAN.
